ALKOXYLATED QUATERNARY AMMONIUM SALTS OF ESTERS OF SALICYLIC ACID AS MICROBICIDES

Elizabeth L. Fareri, Pittsburgh, Robert J. McGuire, Monroeville, and Edward Mitchell, Valencia, Pa., assignors to Gulf Research & Development Company, Pittsburgh, Pa., a corporation of Delaware
No Drawing. Filed Aug. 2, 1965, Ser. No. 476,666
8 Claims. (Cl. 44—63)

ABSTRACT OF THE DISCLOSURE

Alkoxylated quaternary ammonium salts of esters of salicylic acid are used as microbicides in hydrocarbon oil.

This invention relates to chemical compounds and to compositions containing said compounds.

The chemical compounds of this invention are alkoxylated quaternary ammonium salts of esters of salicylic acid. These compounds have been found to exhibit high microbical activity when present in a minor concentration in a hydrocarbon oil, such as fuel oil. The compounds of this invention are especially microbically effective when utilized in a hydrocarbon oil which is in contact with a water phase or is otherwise in a condition conducive to microbial growth.

The alkoxylated quaternary ammonium salicylates of this invention can be selected from compounds having the general structure

wherein:

R is a normal or iso alkyl, normal or iso alkenyl, aralkyl or cycloalkyl substituent containing 1 to 22 carbon atoms and can be substituted with substituents such as nitrogen, halogen, phosphorus, sulfur or oxygen,

R' may be absent or is a normal or iso alkyl, a normal or iso alkenyl, aralkyl, or cycloalkyl substituent containing 1 to 22 carbon atoms and can be substituted with substituents such as nitrogen, halogen, phosphorus, sulfur or oxygen,

R_a is

R_b is

where x=0 to 2, and y+z=2 to 15,

R_c and R_d are each a normal or iso alkyl, a normal or iso alkenyl, aralkyl, or cycloalkyl substituent containing 1 to 22 carbon atoms which can be substituted with substituents such as nitrogen, halogen, phosphorus, sulfur or oxygen, at least one of said substituents containing at least 4 carbon atoms,

N is nitrogen and can be the nitrogen member of a heterocyclic nitrogen-containing ring such as imidazoline,

2

pyridine, thiazine or piperazine, in which case R_c and R_d are part of the heterocyclic ring, C is carbon, and O is oxygen.

Preferred compounds include

where R_a is a C₈- to C₁₈-alkyl substituent such as oleyl; R can be octyl, isoctyl, dodecyl, tridecyl or hexadecyl; and x+y=2.

Salicylic acid is a convenient starting material in the preparation of the alkoxylated quaternary ammonium salicylates of this invention. Salicylic acid contains an hydroxyl radical and a carboxylic acid radical at ortho positions on a benzene ring. In preparing the quaternary ammonium salts of this invention, the reactant containing the quaternary ammonium cation is reacted with the hydroxyl radical of the salicylic acid rather than with the carboxylic radical so that the salt formed is a quaternary ammonium phenate rather than a quaternary ammonium carboxylate. However, the carboxylic acid radical is considerably more acidic and therefore more reactive with the quaternary ammonium cation than is the hydroxyl radical and in order for the quaternary ammonium cation to react with the hydroxyl radical rather than with the carboxylic acid radical the salicylic acid must be esterified prior to the reaction thereof with the quaternary ammonium compound. Therefore, the preparation of the quaternary ammonium salt of this invention is a two-step process in which the order of performance of the steps is critical, i.e., the salicylic acid starting material is first esterified by reaction with an alcohol and only after esterification is it converted to a quaternary salt by reaction with a compound such as a quaternary ammonium hydroxide. Following is a specific example of a two-step process for the preparation of a quaternary ammonium salt of an ester of salicylic acid.

EXAMPLE 1

Step 1.—Preparation of isoctyl salicylate from salicylic acid

A mixture containing 900 grams of salicylic acid, 1300 grams (10 moles) of isoctyl alcohol, 30 grams of p-toluenesulfonic acid and 1000 milliliters of toluene was heated at reflux in a 5-liter flask fitted with a Dean and Stark trap. Reflux was continued until no more water collected in the trap. The solution was cooled to room temperature and extracted with one liter of water, then with one liter of 10 percent sodium bicarbonate solution followed by a washing with one liter of water. The extracted solution was dried over anhydrous sodium sulfate, filtered and vacuum distilled. After distillation of toluene and excess isoctyl alcohol, 1568 grams of a clear oil was collected at 150°—160° C. and 3.2 millimeters pressure. Analysis of the product showed 72.21 percent carbon, 8.90 percent hydrogen, 18.21 percent oxygen and a molecular weight of 265. Theoretically, isoctyl salicylate contains 71.9 percent carbon, 8.8 percent hydrogen, and 19.2 percent oxygen, and has a molecular weight of 250.

Step 2.—Preparation of dihydroxyethylmethyleoleylammonium isoctyl salicylate from isoctyl salicylate

To 12.5 grams (0.05 mole) of isoctyl salicylate in 30 milliliters of benzene was added 29.3 grams (0.05 mole based on neutralization equivalent) of dihydroxyethylmethyleoleylammonium hydroxide in isopropanol solution. The mixture was stirred. Solvents, including water of reaction, were removed at reduced pressure with slight heating. The product, dihydroxyethylmethyleoleylammonium isoctyl salicylate, a viscous clear brown liquid, weighed

29.1 grams and had a nitrogen content of 2.17 percent by weight. The theoretical nitrogen content of dihydroxyethylmethylethylammonium isoctyl salicylate is 2.3 percent by weight.

Tests were conducted to illustrate the high microbicidal activity in hydrocarbon oil of compounds of this invention and to show the unusual superiority in microbicidal activity in hydrocarbon oil of the alkoxylation quaternary ammonium salicylates of the invention as compared to similar compounds wherein the hydroxylalkyl substituents of the quaternary ammonium group are replaced by hydroxyl-free alkyl groups or as compared to compounds wherein the entire quaternary ammonium group is replaced by a metal. In each of the tests, 50 milliliters of mycophil broth was sterilized in an autoclave for 15 minutes at 250° F. Thereupon, 300 milliliters of fuel oil, or fuel oil plus additive, was added. The oil-broth mixture was inoculated with a mixed culture of microorganisms from the water bottoms of a domestic fuel oil storage tank. The domestic fuel oil from which the microorganisms were obtained was an oil similar to that employed in the oil-broth mixture. The flask was stoppered with a cotton plug and stored at room temperature in the dark. The samples were examined once each week for 60 days, and the amount of bacterial growth was rated. In the ratings, 0 designates no growth; + designates slight growth; 2+ designates fair growth; 3+ designates good growth; and 4+ designates excellent growth. At a rating of 4+, or in 60 days, each test was terminated. The result of each test is shown in the following table.

Sample:	Microbial growth rating
Control fuel oil ¹	4+ in 11 days
Control fuel oil plus 0.02 percent by weight of dihydroxyethylmethylethylammonium isoctyl salicylate	0 in 60 days
Control fuel oil plus 0.01 percent by weight of dihydroxyethylmethylethylammonium isoctyl salicylate	0 in 60 days
Control fuel oil plus 0.02 percent by weight of di(hydrogenated tallow) dimethylammonium isoctyl salicylate	3+ in 60 days
Control fuel oil plus 0.02 percent by weight of calcium isoctyl salicylate	4+ in 10 days
Control fuel oil plus 0.02 percent by weight of didymium isoctyl salicylate	4+ in 10 days
Control fuel oil plus 0.02 percent by weight of di(hydrogenated tallow) dimethylammonium p-tert-octylphenate	4+ in 21 days

¹ Typical fuel oil inspections:

Gravity: ° API, ASTM D287	35.1
Viscosity SUV: Sec., ASTM D446 100° F.	33.9
Flash, P-M: ° F., ASTM D93	156
Pour: ° F., ASTM D97	30
Carbon residue, D524 on 10% bottoms	0.11
Distillation, ASTM D158:	
Over point	372
End point	625
At 432° F.	percent
At 488° F.	do
At 573° F.	do
Residue	1.1

The above data clearly show that the alkoxylation quaternary ammonium salicylates of this invention have a high microbicidal activity when present in small concentrations in hydrocarbon oil and are remarkably superior in microbicidal activity as compared to similar compounds in which the hydroxylalkyl substituents of the quaternary ammonium group are replaced by hydroxyl-free alkyl substituents or related compounds in which the quaternary ammonium group is replaced by a metal.

The alkoxylation quaternary ammonium salicylates of this invention are oil soluble and can be present in hydrocarbon oils over a wide range of concentrations. For example, they can be generally present in hydrocarbon

oils over a concentration range of about 0.002 to about 10 percent by weight, the higher region of the range being especially useful when preparing a concentrate, or, preferably, over a concentration range of about 0.005 to about 2 percent by weight. Although useful in a wide variety of hydrocarbon oils such as gasoline, jet fuels, diesel fuels, etc., the alkoxylation quaternary ammonium salicylates of this invention are especially useful in fuel oils, including blends of straight run and catalytically cracked fuel oils. Fuel oils containing the compounds of this invention are commonly in contact with a water phase.

Various changes can be made without departing from the spirit of this invention or the scope thereof as defined in the following claims.

We claim:

1. A composition comprising a hydrocarbon oil in contact with a water phase having dissolved in said oil an oil soluble hydroxylated quaternary ammonium salt of an ester of salicylic acid, said salt being a quaternary ammonium phenate with the ester portion thereof formed from an alcohol containing 1 to 22 carbon atoms.

2. The composition of claim 1 wherein there is attached to the ring structure of said salicylic acid an alkyl, alkenyl, aralkyl or cycloalkyl substituent containing 1 to 22 carbon atoms.

3. The composition of claim 1 wherein attached to the quaternary nitrogen atom are the substituents

and

40 where $x=0$ to 2, and $y+z=2$ to 15.

4. The composition of claim 1 wherein also attached to the quaternary nitrogen atom are alkyl, alkenyl, aralkyl or cycloalkyl substituents containing 1 to 22 carbon atoms, one of which contains at least 4 carbon atoms.

5. The composition of claim 1 wherein said hydrocarbon oil is fuel oil.

6. The composition of claim 1 wherein the concentration of said oil soluble salt in said hydrocarbon oil is between about 0.002 and 10 percent by weight.

7. A composition comprising hydrocarbon oil in contact with a water phase containing an oil soluble compound having the structure

wherein R is a substituent containing 1 to 22 carbon atoms,

65 R_a is

70 R_b is

75

where $x=0$ to 2, and $y+z=2$ to 15, and R_c and R_d are each substituents containing 1 to 22 carbon atoms, at least one of which contains at least 4 carbon atoms.

8. A composition comprising hydrocarbon oil in contact with a water phase and containing about 0.002 to 10 percent by weight of an oil soluble compound having the structure

wherein R is a substituent containing 1 to 22 carbon atoms,

R_a is

10

R_b is

where $x=0$ to 2, and $y+z=2$ to 15, and R_c and R_d are members of the same heterocyclic ring.
